[57] **CLAIM**

The ornamental design of a marine slide, substantially as shown and described.

DESCRIPTION

FIG. 1 is an isometric view from above showing a marine slide embodying the ornamental features of my new design:

FIG. 2 is a top view thereof:

FIG. 3 is an end view thereof; and

FIG. 4 is a bottom view thereof.

The side and end not shown are the same as the side and end shown.
